(57) **CLAIM**

The ornamental design for a pedal crank for bicycle, as shown and described.

DESCRIPTION

FIG. 1 is a top and rear perspective view of a bicycle pedal crank according to the invention;

FIG. 2 is a top and front perspective view of the bicycle pedal crank of FIG. 1;

FIG. 3 is a top plan view of the bicycle pedal crank of FIG. 1; FIG. 4 is a bottom plan view of the bicycle pedal crank of FIG. 1;

FIG. 5 is a rear view of the bicycle pedal crank of FIG. 1;

FIG. 6 is a front view of the bicycle pedal crank of FIG. 1; FIG. 7 is a right side view of the bicycle pedal crank of FIG. 1; and,

FIG. 8 is a left side view of the bicycle pedal crank of FIG. 1.

1 Claim, 8 Drawing Sheets
